UNITED STATES PATENT OFFICE.

ROBERT W. WIEDERWAX, OF ATLANTIC CITY, NEW JERSEY, ASSIGNOR, BY DIRECT AND MESNE ASSIGNMENTS, TO GEIST MANUFACTURING COMPANY, OF ATLANTIC CITY, NEW JERSEY, A CORPORATION OF DELAWARE.

WATER-HEATER.

1,391,354.

Specification of Letters Patent. Patented Sept. 20, 1921.

Application filed December 23, 1920. Serial No. 432,795.

To all whom it may concern:

Be it known that I, ROBERT W. WIEDERWAX, a citizen of the United States, residing at Atlantic City, in the county of Atlantic and State of New Jersey, have invented certain new and useful Improvements in Water-Heaters, of which the following is a specification.

This invention relates to water heaters, and more particularly to means for heating the circulating water in cooling systems of motor vehicles, and it comprises a relatively shallow casing adapted to be arranged in front of the radiator of a motor vehicle, passages communicating with said casing at each side, burner casings arranged in said passages, means for permitting introduction of air into said burner casings in a tortuous path, a casing arranged at the rear of the radiator and provided with outlets, and means for controlling the passage of gases to said outlets.

In certain makes of automobiles, the clearance between the front of the radiator and the starting crank is very small, and it has been difficult to obtain a heating device to be applied to the radiator for heating the circulating water which would not interfere with the cranking of the engine. If the burners are arranged immediately below the casing, it is necessary that the casing be of an appreciable thickness to prevent it from burning out.

In the present invention, I have overcome this difficulty by providing a relatively shallow casing which can be arranged in front of the radiator of any make of automobile and still allow sufficient clearance to permit starting the engine by a hand crank. The burners furnishing heat, are arranged at each side of this casing, and communicate therewith by means of passages. The passage just above the burner may be made of any desired size, without interfering with the cranking operation and without danger of burning out. The products of combustion when conveyed to the relatively shallow casing arranged in front of the radiator are sufficiently cooled to remove the possibility of burning out the walls of the casing.

In the present invention, I have also provided means to prevent an undue amount of air from being supplied to the burner which

would cause improper combustion and would cause the burners to smoke.

Where the products of combustion which heat the circulating air are delivered rearwardly beneath the hood of the motor vehicle, I have found that the fan employed for the purpose of creating a circulation of air through the radiator, draws the products of combustion through the outlets at a rapid rate and causes an excessive inflow of air to the burners. In the present invention, I have provided means for overcoming this difficulty by placing a screen within the rear casing and providing inlets near the bottom of the casing whereby the effect of the draft created by the fan is to draw air through the rear casing only.

In the accompanying drawings, I have shown one embodiment of the invention. In this showing:

Figure 1 is a front elevation of a motor vehicle showing the invention applied,

Fig. 2 is a vertical sectional view on line 2-2 of Fig. 1,

Fig. 3 is a horizontal sectional view on line 3-3 of Fig. 2,

Fig. 4 is a similar view on line 4-4 of Fig. 1,

Fig. 5 is a vertical sectional view on line 5-5 of Fig. 2,

Fig. 6 is a similar view on line 6-6 of Fig. 1,

Fig. 7 is a vertical sectional view on line 7-7 of Fig. 3,

Fig. 8 is a horizontal sectional view on line 8-8 of Fig. 7, and,

Fig. 9 is a similar view on line 9-9 of Fig. 7.

Referring to the drawings, the reference numeral 1 designates generally the radiator of a motor vehicle. The vehicle is provided with a front axle 2, and front wheels 3. It is provided with head lamps 4, supported on a rod or supporting member 5, extending from the frame 6. The usual fenders 7 may be provided.

My improved heater comprises a main casing 8, which is provided with side walls 9 and top and bottom walls 10, whereby a casing is provided open at the back, and closed at the front and sides. As shown, in Fig. 6 of the drawings, the casing is shallow and extends a very slight distance in front

of the radiator, whereby it does not interfere with the operation of the starting crank (not shown). At each side of the casing, a relatively narrow communicating passage 11 is provided which, as shown, extends beyond the sides of the radiator and communicates with a vertical passage 12. The vertical passages which form the combustion chambers and which are submitted to a relatively high degree of heat may be made in any desired size and shape, as they are so far removed from the center of the machine that they will not interfere with the operation of a starting crank.

15 A casing 13, similar in construction to the casing 8 and provided with flanges 14, on four sides, is arranged at the back of the radiator. This casing and the front casing are maintained in position by means of bolts 15 passing through the radiator, the bolts being provided with nuts 16, or other suitable fastening elements.

A burner casing or chamber 17 is arranged at the bottom of each of the vertical passages 12. An oil receptacle 18 is adapted to be arranged beneath the burner casing and held in position in any suitable manner. The burner casing is provided with a pair of horizontal partitions 19 and 20, spaced 30 from the bottom 21 and with a sloping top 22. A central opening is provided at the bottom of the vertical passage 12, and this central opening is adapted to receive a burner frame 23, the bottom of which is 35 provided with a flange 24, slightly spaced from the bottom 21 of the burner casing. The burner is provided with a wick 25, which extends downwardly in a wick tube 26, and projects below the bottom of the 40 burner casing, being adapted to be inserted in the oil receptacle. Suitable regulating means 27 are provided for the wick. The wick tube is surrounded by a pair of perforated plates 28 and 29, of the usual construction. Air is admitted to the burner through openings 30, arranged on the sloping top of the burner casing, and extending 45 entirely around the burner (see Fig. 3). Within the chamber formed by the sloping top 22 and the partition 20, there is provided a plurality of openings 31 extending along two sides. A screen 32 is arranged between the openings 30 and 31, the air in passing through the upper portion of the 50 burner casing being caused to pass through the screen. An air chamber 33 is provided between the partitions 19 and 20, and the partition 19 is provided with two rows of 55 openings 34, arranged out of alignment with the openings 31 in the partition 20. Screens 35 are arranged in the chamber 33 between the two sets of openings. When the air passes into the bottom of the burner casing, it is caused to find its way beneath the flange 60 65 24 to enter the burner.

As shown, the junction of the passages 11 and the vertical passages 12 is rounded on the upper side, as at 36 (see Fig. 5), and a curved plate 37 is arranged on the lower wall substantially parallel to the curved 70 portion 36.

The rear casing 13 is provided with outlet openings 38. A screen or perforated plate 39 is arranged within this casing between the openings 38 and the radiator. A plurality of air inlet openings 40 are provided at any suitable point in the plate, the position of the openings being optional. The openings are disposed to permit air passing into the casing to reach the outlet openings 80 38, without passing through the screen 39.

The operation of the device is as follows:

The heater is attached to the radiator of a motor vehicle by means of bolts 15. The burners are lighted and the products of combustion pass upwardly through the vertical passages 12, the communicating passages 11, to the front casing 8, thence through the radiator, heating the circulating water or other fluid, into the rear casing 90 13, and through outlet openings 38. The provision of the screen 39 prevents flames from the engine from entering the heater and casing, and causing a fire in the oil receptacles 18. By providing a curved wall 95 36 between the passages 11 and 12, and the curved plate 37, forming a substantially parallel wall on the opposite side, more perfect combustion is obtained as the flow of gases and products of combustion is less 100 obstructed than where square corners are provided. Air is supplied to the burners through openings 30, screen 32, openings 31, screen 35 and openings 34. The provision of a tortuous passage for the introduction of air is advantageous, in that, it permits use of the heater while the vehicle is running. If means are not provided for regulating the admission of air, the supply of air furnished to the burner when the vehicle is running is too great and a smoky 110 flame results which is disadvantageous.

The provision of inlet openings 40 in the rear casing, together with the screen 39, overcomes a disadvantage of prior constructions, in that, the operation of the fan when the engine is running draws air through the openings 40 and the opening 38 without materially affecting the natural passage of the products of combustion through the heater. 115 In the absence of the inlet openings 40 and the screen 39, the fan has a tendency to create an induced draft throughout the heater and cause circulation at such a rapid rate that the oil or other fuel is not completely burned, resulting in the presence of smoke and other undesirable features.

It is to be understood that the form of my invention herewith shown and described is to be taken as a preferred example of the 120 125 130

same, and that various changes in the shape, size, and arrangement of parts may be resorted to without departing from the spirit of the invention or the scope of the sub- 5 joined claims.

Having thus described my invention, I claim:

1. In a device for heating the circulating fluid in cooling systems of motor vehicles, 10 the combination with a radiator, of a relatively shallow casing arranged in front of said radiator, a casing arranged in the rear of said radiator, and burner casings arranged at each side of said front casing and 15 communicating therewith.

2. In a device for heating the circulating fluid in cooling systems of motor vehicles, the combination with a radiator, of a relatively shallow casing arranged in front of 20 said radiator, a casing arranged in the rear of said radiator, passages communicating with said front casing at each side, and burner casings arranged in said passages.

3. In a device for heating the circulating fluid in cooling systems of motor vehicles, 25 the combination with a radiator, of a casing arranged in front of said radiator, a casing arranged in the rear of the radiator, burner casings arranged at each side of said front casing, and means for delivering air to each 30 of said burner casings through a tortuous path.

4. In a device for heating the circulating fluid in cooling systems of motor vehicles, 35 the combination with a radiator, of a casing arranged in front of the radiator, burner casings arranged at each side of said casing, burners arranged within said burner casings, the tops of said burner casings being 40 provided with a plurality of openings, and means for delivering air from said openings in the top of each of said burner casings to said burners through a tortuous path.

5. In a device for heating circulating fluid 45 in cooling systems of motor vehicles, the combination with a radiator, of a casing arranged in front of the radiator, burner casings arranged at each side of said casing, burners arranged within said burner 50 casings, the tops of said burner casings being provided with a plurality of openings, and horizontal partitions arranged in said burner casings, said horizontal partitions being provided with openings staggered with

relation to the openings in the top of the 55 burner casing.

6. In a device for heating circulating fluid in cooling systems of motor vehicles, the combination with a radiator, of a casing arranged in front of the radiator, a casing 60 arranged in the rear of the radiator, burner casings arranged at each side of said front casing, burners arranged within said burner casings, the tops of said burner casings being 65 provided with a plurality of openings, said burner casings being provided with horizontal partitions dividing said burner casings into a plurality of chambers, said partitions being provided with openings staggered with relation to the openings in 70 the top of the casing whereby air passing through said casing to the burner will travel in a tortuous path, and perforated plates arranged in said chambers in the path of travel of the air.

7. In a device for heating the circulating fluid in cooling systems of motor vehicles, the combination with a radiator and a fan arranged in the rear of the radiator, of a 80 casing arranged in front of said radiator, a casing arranged in the rear of said radiator burners arranged in said front casing, and means in said rear casing to prevent the creation of a draft within said heater by the fan.

8. In a device for heating the circulating fluid in cooling systems of motor vehicles, the combination with a radiator and a fan arranged in the rear of the radiator, of a 85 casing arranged in front of said radiator, a casing arranged in the rear of the radiator burners arranged in said front casing, said rear casing being provided with outlet openings, and a screen arranged within said rear casing and in the path of said 90 heated gases, said rear casing being provided with a second set of openings positioned to permit introduction of air into said rear casing and discharge the same through said outlet openings without passing through said screen.

In testimony whereof I affix my signature in presence of two witnesses.

ROBERT W. WIEDERWAX.
